UNITED STATES PATENT OFFICE.

LYTH F. EVENSON, OF SILVERTON, OREGON; NORA EVENSON EXECUTRIX OF SAID
LYTH F. EVENSON, DECEASED.

ADJUSTABLE FEED FOR FOUNTAIN PENS.

Application filed June 4, 1923. Serial No. 643,386.

To all whom it may concern:

Be it known that I, LYTH F. EVENSON, a citizen of the United States, residing at Silverton, in the county of Marion and State 5 of Oregon, have invented new and useful Improvements in Adjustable Feed for Fountain Pens, of which the following is a specification.

This invention relates to fountain pens 10 and has for its object the provision of a novel feed device which is adjustable whereby to regulate the quantity of ink flowing to the pen point, the means for effecting the adjustment being operated from the exterior 15 of the pen without it being necessary to disconnect or remove any of the parts.

An important object is the provision of a feed of this character which may be used in connection with pens of the so-called self-filler type as well as the ordinary type requiring filling by means of a dropper or the like.

An additional object is the provision of a feed of this character which will be simple 25 and inexpensive in manufacture, easy to control, positive in action, efficient and durable in service and a general improvement in the art.

With the above and other objects and 30 advantages in view the invention consists in the details of construction to be herein-after more fully described and claimed and illustrated in the accompanying drawings, in which:

Figure 1 is a longitudinal section through 35 a portion of a fountain pen embodying my invention,

Figure 2 is a similar view showing a different position of the adjusting means and

Figure 3 is a detail cross section on the line 3—3 of Figure 1.

Referring more particularly to the drawings the numeral 10 designates the shell or body which closes one end of the usual barrel 11 and which is formed with an extension 12 upon which is secured the ink bag, not shown, in case the pen be of that type which is so-called self filling. In the type of pen requiring filling by means of a dropper there is no bag employed but this detail does not affect the present invention one way or the other.

Mounted within one end of the member 10 is a detachable or removable pen point 55 13 of usual construction, the point being

held frictionally in place in the ordinary manner.

The essential feature in the present device is the provision of an elongated member 14 which is located within a bore 15 in the body 60 10 and which extends to a point substantially midway of the pen. One side of this member 14 is slotted as shown at 16 and this slot is substantially T-shaped in cross section with its bottom wall 17 inclined as 65 shown. This slot communicates with a duct 18 in one edge of the member 14, which duct terminates short of the outer end of the member and is for the purpose of conducting ink to the pen. The member 14 is further formed with a longitudinally extending 70 passage 19 for a purpose to be described.

Slidable along the slot 16 is a regulating wedge 20 which is of a cross sectional shape 75 to fit within the slot and which has an inclined wall 21 co-operating with the inclined bottom 17 of the slot. While it is not absolutely necessary the top of this wedge member may be fluted or grooved as indicated at 80 22 so as to permit the flow of a certain quantity of ink even though a wedge member may be in its innermost position filling the slot. The control means for this wedge member consists of an elongated rod 23 which extends through the passage 19 and 85 which has one end extended laterally as shown at 24 and secured within the larger or inner end of the wedge member. This rod extends beyond the body so as to be exposed and the projecting end is formed with 90 a plurality of notches 25 within any one of which may be engaged the thumb nail of the operator for the purpose of adjusting the position of the rod. The number of notches exposed will also serve as a guide to indicate the position of the movable wedge member.

In the operation it is of course apparent 100 that the flow of the ink is controlled by the position of the wedge member, it being obvious that when the wedge is pulled toward the pen point the flow will be reduced. By proper manipulation the exact rate of feed may be regulated to meet the requirements 105 of the individual user. The operation and construction are both very simple and the device has proved to be extremely efficient and satisfactory in every way.

While I have shown and described the 110 preferred embodiment of the invention it

is of course to be understood that I reserve the right to make such changes in the form, construction and arrangement of parts as will not depart from the spirit of the invention or the scope of the subjoined claims.

Having thus described my invention I claim:

1. In a fountain pen, a body carrying a pen point and formed with a bore, a feed bar located within the bore and having an inclined slot communicating with a duct leading to the pen point, a wedge slidable along said slot, and a handle member slidable longitudinally of the feed bar and connected with said wedge.

2. In a fountain pen, a body carrying a pen point and formed with a bore, a feed bar located within the bore and having an inclined slot communicating with a duct leading to the pen point, a wedge slidable along said slot, and a handle member slidable longitudinally of the feed bar and connected with said wedge, said handle member being formed with means for engagement by a thumb nail for effecting movement.

3. In a fountain pen, a body carrying a pen point and formed with a bore, a feed bar located within the bore and having an inclined slot communicating with a duct leading to the pen point, a wedge slidable along said slot, and a handle member slidable longitudinally of the feed bar and connected with said wedge and indicating means on the projecting end of the handle member for indicating the position of the wedge.

4. In a fountain pen, a body carrying a pen point and formed with a bore, a feed bar located within the body and formed with a slot and a duct leading to the pen

point, an adjustable closure member for said slot, and operating means for the closure member including a rod slidable longitudinally through the feed bar and having its inner end operatively connected with said closure means and its outer end formed to constitute a handle for shifting the position of the closure member.

5. In a fountain pen, a body carrying a pen point and formed with a bore, a member located within the bore and formed with a slot having an inclined bottom and leading to a duct extending to the pen point, a wedge slidable along said slot and means for moving said wedge, including a rod having one end secured to the wedge and slidable along a passage in said member, the rod projecting beyond said member and having its projecting end formed with a notch engageable by the thumb nail for effecting movement of the wedge.

6. In a fountain pen, a body carrying a pen point and formed with a bore, a member located within the bore and formed with a slot having an inclined bottom and leading to a duct extending to the pen point, a wedge slidable along said slot and means for moving said wedge, including a rod having one end secured to the wedge and slidable along a passage in said member, the rod projecting beyond said member and having its projecting end formed with a plurality of notches selectively engageable by a thumb nail for moving the wedge, the number of notches exposed indicating the position of the wedge.

In testimony whereof I affix my signature.

LYTH F. EVENSON.
